UNITED STATES PATENT OFFICE.

LORENZO ZUNINO, OF BERKELEY, CALIFORNIA.

DESIGN FOR A PEDESTAL.

Application filed June 5, 1922. Serial No. 2,526. Term of patent 3½ years.

To all whom it may concern:

Be it known that I, LORENZO ZUNINO, a subject of the King of Italy, and a resident of the city of Berkeley, county of Alameda, State of California, have invented a new, original, and ornamental Design for a Pedestal, of which the following is a specification, reference being had to the accompanying drawings, forming part thereof.

The figure is a perspective view of the pedestal viewed from the front.

I claim:

The ornamental design for a pedestal, substantially as shown.

LORENZO ZUNINO.
